(57) CLAIM

The ornamental design for gun scope, as shown.

DESCRIPTION

FIG. 1 is a front perspective view of gun scope showing my new design;

FIG. 2 is a front view thereof;

FIG. 3 is a rear view thereof;

FIG. 4 is a left view thereof;

FIG. 5 is a right view thereof;

FIG. 6 is a top side view thereof; and,

FIG. 7 is a bottom side view position.

FIG. 8 is a front perspective view of a second embodiment of a gun scope showing my new design;

FIG. 9 is a front view thereof;

FIG. 10 is a rear view thereof;

FIG. 11 is a left view thereof;

FIG. 12 is a right view thereof;

FIG. 13 is a top side view thereof; and,

FIG. 14 is a bottom side view position.

The broken lines shown in all views are to illustrate environment only and form no part of the claimed design.
